CLAIM

The ornamental design for a rattlesnake mug, as shown and described.

DESCRIPTION

The rattlesnake mug is a drinking mug designed to resemble various parts of a rattlesnake.

FIG. 1 is a front, perspective view of decorative sculpture of a rattlesnake mug showing my new design;

FIG. 2 is a top view thereof;

FIG. 3 is a right side, perspective view thereof;

FIG. 4 is a left side, perspective view thereof;

FIG. 5 is a back, perspective view thereof;

FIG. 6 is a bottom view thereof; and,

FIG. 7 is a top front right perspective view thereof.
